CONTAINER

Conrad W. Johnson, Jamestown, N. Y.

Application October 15, 1934, Serial No. 748,420

2 Claims. (Cl. 312—34)

This invention relates to an improvement in containers for various articles such as cigarettes, cigars, matches, etc., being particularly directed to the provision of means for dispensing one article at a time from the container as desired.

The present embodiment of the invention discloses a container adapted for use in dispensing articles such as cigarettes, including cover means in the form of an ash receptacle and means for 10 removably mounting the container in position of use.

In prior devices of this character, it has been found that considerable difficulty is encountered in their proper use. The operating mechanism, 15 by which one article may be dispensed, either fails to deliver a single article or in so doing breaks or damages the articles remaining in the container. The more fragile articles to be dispensed from a device of this nature, such as cigarettes, have a tendency to become packed or compressed in the container thus tending to prevent their downward movement by gravity into the dispensing mechanism. To insure proper feeding of one article after the other into 20 the dispensing mechanism, it is necessary that the articles within the container be agitated each time the dispensing mechanism is manipulated in order that one by one they may freely move into said mechanism.

30 The provision of a dispensing container which functions to deliver only one article at a time constitutes the principal object of the invention.

Another object of the invention lies in the provision of a device of this character having means 35 by which to completely close access from the interior of the container to the delivery opening during the operation of dispensing one article.

A further object of the invention lies in the provision of a device of this character in which 40 an agitator functions to move all of the articles within the container during each dispensing operation.

A still further object of the invention lies in the provision of a device of this character having 45 means for attachment to a generally vertical surface by which to facilitate use thereof.

Other and further objects of the invention will be more fully understood from a consideration of the following specification taken in conjunction with the accompanying drawing and in 50 which,

Figure 1 is a perspective view of a container embodying one form of this invention, showing means by which the container may be mounted;

55 Figure 2 is a perspective sectional view of the

container showing the dispensing and agitating mechanism;

Figure 3 is a front elevation of the container partly in section to show the method of mounting the dispensing mechanism; 5

Figure 4 is a view of the agitator and dispensing mechanism removed from the container;

Figure 5 is a fragmentary vertical sectional view of the pivotal support for the dispensing mechanism; and 10

Figure 6 is a fragmentary vertical sectional view of the container showing the dispensing mechanism in position to dispense one article and the agitator in position to move the contents of the container, the dotted line position being 15 similar to the position of the mechanism as shown in Figure 2.

Reference is now had to the drawing in which is shown one modification of the invention in the form of a container generally indicated by 20 the reference numeral 10. The container may include a front wall 11 connected by side walls 12 and 13 and rear wall 14. The length of the walls enumerated is such as to accommodate articles desired to be dispensed. The upper opening of the container is closed by a cover 16. This cover may be provided with an inner flange 17 which seats against the inner edges of the walls 11, 12, 13 and 14. The cover includes a base wall 18 and may, as shown in the drawing, be provided with upwardly and inwardly directed walls 20 which form a generally rectangular opening 21. Thus the cover may provide a compartment 22 in the form of an ash receiver. If the cover is thus used and the container 10 is formed from 25 material other than metal, it will be found desirable to provide a metal liner to prevent charring or burning of the walls of the receiver. It is also contemplated that the walls 20 of the cover may provide a receiver for loose matches or a 30 box of matches, this being optional with the user of the device. The bottom wall 24 of the container may be a continuation of the rear wall 14, being inclined, however, at an angle thereto and directed toward the lower edge of the front wall 11. The front wall 11 adjacent the termination 35 of the bottom wall 24 is inwardly curved to provide a rolled bead 25. As hereinafter may be more fully understood, the bead 25 cooperates with a portion of the dispensing mechanism to prevent jambing and the consequent mutilation 40 of articles within the container prior to their being dispensed. The space between the bead 25 and the forward edge of wall 24 receives a dispensing mechanism for the container. 45

50

55

The container dispensing mechanism 26 comprises end portions 27 each having an opening 28 therethrough. The inner face of each of the portions 27 is provided with a recess 29 concentric with the opening 28. Secured to or formed integral with the end portions 27 is an article receiver 31 which is proportioned to contain only one article at a time of the class of articles to be dispensed from the container. The rear wall 32 of the receiver 31 is somewhat enlarged to form a bead 33. One or more transverse notches 34 are cut transversely of the bead. Adjacent the forward edge of the article receiver is a rib 36 which constitutes the means by which the dispensing mechanism may be manipulated. The end walls 12 and 13 are formed with openings 38 which correspond in size with the openings 28 in the end portions 27 of the dispensing mechanism 26. A pin 39 having a head 40 is inserted from the inner face of the portion 27 through the openings 28 and 38, the head 40 being of a size to fit the recess 29 in the portion 27. The pins 39 constitute the pivotal support for rotational manipulation of the dispensing mechanism. It will be noted that the rear wall 32 of the receiver 31 lies adjacent the lowermost edge of the inclined wall 24 of the container and that the forward wall directly above the rib 36 is adjacent the lower thickened portion of the front wall 11. Thus the lower opening of the container is effectually closed. Now it is desired that the dispensing mechanism after being manually actuated return to its position of disuse to close the dispensing opening of the container 10. To accomplish this a comparatively heavy weight 42 is located on the underside of the dispensing mechanism directly beneath the pins 39.

An agitator plate 43 is located within the container on the inclined wall 24 thereof. This agitator is tapered having a knife-like rear edge 44 and a comparatively thick front edge 45. Projecting from the front edge 45 are arms 46 which enter the recesses 34 of the bead 33. A pin 47 or other pivotal means connects the arms 46 with the bead 33.

It is contemplated that this device is well adapted as a container for cigarettes and that it may be conveniently mounted on any generally upright wall. The rear wall 14 is, therefore, provided with a pair of angle plates 48 from which outwardly extending lugs 49 project. Each lug is formed with an opening 50. A bracket 51 having side flanges 52 is located in the space between the lugs 49 and suitable pins 53 pivotally secure the bracket to the container. Slots or other openings 54 may be provided in the bracket 51 by means of which said bracket may be engaged with any suitable wall through the use of screws. It is contemplated that a device of this character may be mounted on a table standard which may be connected with the bracket 51 or directly to the side walls 12 and 13 in the container.

The dispensing mechanism when not in use occupies the position shown in Figure 2 of the drawing, the agitator plate 43 lying on the inclined wall 24 with its edge 44 adjacent the connection of the wall 24 with the wall 14. The receiver 31 closes the lower opening of the container 10. The cover 16 may be removed and articles such as cigarettes 55, shown in Figure 5 of the drawing, inserted. The cigarettes will drop down the inclined surface of the plate 43, one falling into the receiver 31. The cover is

again placed on the container and the device is ready for operation.

To deliver the cigarette located in the receiver 31 it is merely necessary to rotate the dispensing mechanism about the pins 39 by pressing rearwardly upon rib 36. This movement provides an opening between the front edge of the receiver and the bead 25 and allows the cigarette to drop into the hand of the operator. Simultaneously with the delivery of the cigarette, the rear wall 32 of the receiver has moved upwardly and forwardly carrying with it the agitator plate 43. The cigarettes remaining in the container and lying upon the plate 43 are lifted away from the dispensing mechanism. The cigarette next in order to be dispensed, as indicated in dotted lines in Figure 6, does not lie upon the plate 43. The bead 33, however, of the dispensing mechanism strikes this cigarette moving it over the bead 25 and upwardly along the curved surface of the wall 11 elevating this cigarette by means of bead 33 and the remainder of the cigarettes by plate 43 agitates all of the cigarettes in the container sufficiently to prevent their becoming packed or compressed. Upon the delivery of a cigarette the operator removes his hand from the rib 36. The weight 42 now functions to rotate the receiver about the pins 39 to close the delivery opening of the container moving the dispensing mechanism again to the position shown in Figure 2 of the drawing. Since the receiver 31 has been emptied another cigarette will move by gravity thereinto and the device is again ready for use.

It will be noted that the forward edge of the agitator plate 43 contacts the curved wall of the rear wall 32 of the receiver 31 when said receiver is rotated to dispense an article (see Figure 6). Inasmuch as oscillation of the receiver is in the form of a flipping motion, the forward edge of plate 43 strikes the receiver and the rear edge of said plate is thereby projected or flipped upwardly causing the articles thereon to be tumbled and moved by gravity down the inclined surface of the plate.

Although applicant has shown and described only one modification of a container and dispensing mechanism for articles it is contemplated that other modifications or adaptations of the structure herein shown and described may be made without departing from the spirit and scope of the invention as defined in the hereunto annexed claims.

Having thus set forth my invention what I claim as new and for which I desire protection by Letters Patent is:—

1. In a dispensing container having a delivery opening, a mechanism for dispensing articles from said container, said mechanism being located in said opening and comprising an article receiver, means pivotally supporting said receiver, said receiver being rotatable to close said delivery opening, a plate in said container constituting a false base thereto, means pivotally connecting the forward edge of said plate to the rear edge of said receiver, said plate, during one complete oscillation of said receiver, being constrained to move forwardly and upwardly from off the base wall of the container whereby to agitate or tumble articles in the container during each dispensing operation.

2. In a dispensing container having a delivery opening, a mechanism for dispensing articles from said container, said mechanism being located in said opening and comprising an article

receiver, means pivotally supporting said receiver, said receiver being rotatable to close said delivery opening, a plate in said container constituting a false base thereto, means connecting the forward edge of said plate to the rear edge of said receiver, said means providing limited pivotal movement between said receiver and said plate

5 whereby, during oscillation of said receiver to dispense an article, said plate will be momentarily raised from off the base wall of the container for the purpose of agitating and moving articles within the container downwardly along said plate 5 toward said receiver.

CONRAD W. JOHNSON.
